J. NAWARYNSKI

ANTI THEFT ALARM DEVICE

Filed April 18, 1927

Fig. 3.   Fig. 4.

INVENTOR
John Pawarynski
BY
Gottlieb Black, Esq.
ATTORNEY

UNITED STATES PATENT OFFICE.

JOHN NAWARYNSKI, OF CLEVELAND, OHIO.

ANTITHEFT ALARM DEVICE.

Application filed April 18, 1927. Serial No. 184,455.

This invention relates to mechanism for sounding an alarm when a window is raised and has for one of its objects the provision of an adjustable means adapted to predetermine the height to which a window must be raised to actuate the alarm.

Another object of the invention is the provision of alarm mechanism which is adapted to be securely concealed in the sash and frame of a window.

Other objects will appear hereinafter the novel combinations and features being set forth in the appended claims.

In the drawing:

Fig. 1 is a front elevational view of a window and frame thereof embodying my invention;

Fig. 2 is a vertical fragmentary sectional view of a window sash and a window frame embodying my invention;

Fig. 3 is a side elevational view of the window frame shown in Fig. 2.

Fig. 4 is a side elevational view of the window frame shown in Fig. 2; and

Referring particularly to the drawing the numeral 10 designates a window frame and the numeral 11 designates a window sash. The window sash 11 is provided with a recess 12 in the vertical edge 13 thereof. The recess 12 is confined between the inner and outer surfaces of the frame 11 and has an irregular back, the lower portion of the recess being extended further into the frame than the higher portion thereof. A resilient strip member is rigidly secured at its upper end to the sash 11 by the screw 15. The resilient strip 14 is depended downwardly into the enlarged lower portion of the recess 12. On the lower end of the strip 14 are mounted spaced bearing members 16 and 17 having openings therein in which a pin 18 is rigidly secured. A roller 19 is rotatively mounted on the pin 18.

The frame 10 is provided with an elongated recess 20 extending through from side to side thereof. A vertical partition 21 having a vertically disposed slot 22 therein is disposed in the recess 20 and extends the entire length thereof. A block 23 comprising screw-threaded extensions 24 is slidably mounted in left side of the partition 21 as viewed in Fig. 2. Longitudinal slots 25 and 26 spaced on opposite sides of the slot 22 are provided in the partition 21 to receive the screw-threaded extensions 24. Thumb screws 27 are screw threaded in the extension

24 for clamping the block 23 firmly against the partition 21 in a desired vertical position. A resilient lever or spring strip 28 is rigidly mounted at one end on the block 23 and engages one end of a pin 24' slidably mounted in an opening in the block 23 and is extended at its other end through the recess 22 in the partition 21. The end of the pin 24' engages one surface of the spring strip 28 and the roller 19 engages the opposite surface thereof as shown in Fig. 2. It should be understood that the spring strip 14 of the window is urged in the direction of spring strip 28 of the window frame by a coil spring 14' mounted at one end in a socket 15' in the recess 12. It should also be understood that the spring strip 28 is mounted in the path of the roller 19 and that the free end of the said strip is disposed in the direction of the roller.

Spaced contact members 29 and 30 comprising substantially resilient elements are mounted in the recess 20 in registration with the longitudinal opening 22 in the partition 21. The contact members 29 and 30 are provided with a plurality of spaced apart, inwardly directed projections 31 and 32 respectively.

As shown in Fig. 1, a conductor 34 is electrically connected at one end to the contact strip 30 and at the other end to one terminal of the bell 35, the other terminal of the bell being electrically connected with one terminal of a source of power such as a battery 36. The contact strip 29 is electrically connected with the other terminal of the battery 36 by a conductor 37. The spaced contact members 29 and 30 normally tend to remain in parallel planes and are electrically insulated from each other. The outer end 38 of the pin 24' engages the contact strip 29 and deflects the latter as shown in Fig. 2 when the pin is pressed inwardly by the strip 28 when the roller 19 engages the free end portion thereof. The contact strip 29 is provided at its upper end with a curved portion 39 which permits outward movement of the portion of said strip intermediate the ends thereof.

The slidable block 23 may be secured in any desired position in the recess 20 for predetermining the height to which the window must be raised to actuate the alarm mechanism. It should be understood that the block 23 may be clamped against the partition 22 by the thumb screws 27. When the

pin 24' of the block 23 is pressed outwardly by the member 28 it deflects the contact strip 29 causing engagement between the projections 31 of said strip and the projections 32 of the other contact strip 30, thus completing an electric circuit and causing the bell 35 to be actuated.

Having thus fully described and shown an embodiment of my invention what is desired to be secured by Letters Patent of the United States is:

1. An electric switch mechanism for windows comprising contact members disposed in a window frame, and an adjustable member mounted in said frame adapted to predetermine the height to which a window must be raised to actuate said alarm.

2. An electric switch mechanism for windows comprising spaced contact members mounted in a recess in the frame of a window, an adjustable member slidably mounted in said recess, a pin slidably mounted in said adjustable member and engaging one of said contact members, and means on the sash of said window for pressing said pin inwardly to cause engagement of said contact members.

3. An electric switch mechanism for windows comprising a window sash and a window frame provided with recesses in the adjacent edges thereof, a vertical partition having spaced longitudinally extending slots therein mounted in the recess of said window frame, a slidable block mounted on one side of said partition adapted to move longitudinally therein, screw threaded extensions on said block disposed through said spaced recesses, a thumb screw screw-threaded on said extension for adjustably clamping said block in a suitable position, a pin slidably mounted in said block and extended through a central longitudinal slot in said partition, spaced contact members mounted in the recess in said frame in registration with the central longitudinal slot therein, one of said contact

members being in engagement with the end of said pin, resilient member mounted on said block for retaining said pin in engagement with said contact member, and means comprising a roller mounted in the recess in said window sash adapted to urge said resilient member and said pin inwardly for causing engagement of said contact member when said window is raised.

4. In electric switch mechanism for windows comprising a window sash and a window frame provided with recesses in the adjacent edges thereof, a vertical partition having spaced longitudinally extending slots therein mounted in the recess of said window frame, a slidable block mounted on one side of said partition adapted to move longitudinally therein, screw threaded extensions on said block disposed through said spaced recesses, a thumb screw screw-threaded on said extension for adjustably clamping said block in a suitable position, a pin slidably mounted in said block and extended through a central longitudinal slot in said partition, spaced contact members mounted in the recess in said frame in registration with the central longitudinal slot therein, one of said contact members being in engagement with the end of said pin, a resilient member mounted on said block for retaining said pin in engagement with said contact member, a resilient member mounted in the sash of said window, and a roller rotatively mounted on said resilient member adapted to engage the resilient member of said block when said window is raised for urging said pin inwardly to cause engagement of said spaced contact members, said block being adjustable to predetermine the height to which the window must be raised to cause engagement of said roller with the resilient member of said block.

In testimony whereof I have affixed my signature.

JOHN NAWARYNSKI.
